UNITED STATES PATENT OFFICE

2,357,227

ATOMIZING SPREADER FOR SPRINKLER HEADS

Arthur C. Rowley, Drexel Hill, Pa., assignor to
Globe Automatic Sprinkler Company, Philadelphia, Pa., a corporation of Pennsylvania

Application March 13, 1943, Serial No. 479,088

4 Claims. (Cl. 169—39)

A principal object of this invention is to provide an improved atomizing spreader primarily for the sprinkler heads of automatic fire-extinguishing systems.

Another object of the invention is to provide an improved atomizing sprinkler head incorporating the said spreader, as hereinafter described.

The invention will be more readily understood by reference to the attached drawings, wherein

Fig. 1 is a side view of a sprinkler head made in accordance with the invention;

Fig. 2 is a sectional view on the line 2—2, Fig. 1;

Fig. 3 is a sectional view on the line 3—3, Fig. 1;

Fig. 4 is a sectional view on the line 4—4, Fig. 1;

Fig. 5 is a side and partial sectional view of the sprinkler head illustrating the mode of operation.

With reference to the drawings, the sprinkler head therein illustrated is of known form with the exception of the spreader element and the parts of the frame immediately associated with the spreader. The frame comprises a yoke 1 having at its outer end, and in alignment with the discharge port or nozzle 2 of the head, a threaded opening for reception of a screw 3 to which the spreader 4 is attached. The port 2 is normally closed by valve disk 5 held in place by the screw 3 acting through a fusible link 6 of suitable form. A link of the form illustrated is disclosed in my copending application, Serial No. 479,089 filed March 13, 1943.

The spreader 4 comprises two sections, 7 and 8, which function respectively as primary and secondary deflectors and which co-act in a manner hereinafter described to produce the desired atomizing effect upon the stream of liquid discharged from the system through port 2 when the valve disk 5 is displaced. The primary deflector 7, which lies closest to the port 2 and which is first contacted by the stream of discharged liquid, comprises a plurality of narrow radiating arms 9 separated by narrow intervening spaces 11. In the present instance, the arms 9 extend radially from a common center at the axis of the screw 3 which also is the axis of the discharge nozzle 2. Preferably, the outer ends of the arms 9 are notched as indicated at 12. The secondary deflector 8 is spaced axially from the primary deflector and takes the form in the present instance of a solid disk which is coaxial with the primary spreader and is of lesser radial extent so that it overlies an inner portion only

of the several intervening spaces 11. This relationship of the secondary deflector to the primary deflector is best shown in Fig. 3. Preferably the corner where the under surface of the disk joins the stem is filleted as indicated at 10, see Fig. 2.

The mode of operation of the deflector is illustrated in Fig. 5 wherein the sprinkler head is shown after displacement of the valve disk 5 and its retaining link 6. The stream of liquid discharging through the port 2 is indicated by the reference numeral 13. This stream impinges first upon the under side of the primary deflector 7 and is broken up by the arms 9, it being noted that the arms are slightly inclined from the normal plane toward the nozzle. Certain portions of the stream 13, however, pass more or less intact through the spaces 11 and the notches 12 and some of these solid components, namely those which pass through the inner ends of the spaces, impinge forcibly against the opposed surface of the secondary deflector and are projected by that deflector laterally at high velocity. This action of the deflector is well illustrated in Fig. 5. The high velocity particles thus deflected laterally by the secondary deflector impinge upon the other solid components which have passed the primary deflector through the spaces 11 and the notches 12 and the impingement results in a mutual atomization of the particles. As a result of the joint action of the primary and secondary deflectors, substantially the entire body of liquid passing from the nozzle 2 is broken up into minute particles and is widely distributed in the atomized condition.

Operating in conjunction with the deflector device described above and contributing to the atomizing efficiency of the device as a whole is a formation of the yoke 1 in the area embracing the screw 3 and immediately underlying the primary deflector 7. It will be noted by reference to Fig. 1 that the yoke is channeled at each side of the central boss 14 which receives the screw 3, these channels being indicated by the reference numeral 15. The two channels at each side of the yoke converge toward the underside of the deflector and the outer ends of the channels terminate in proximity to the inner ends of the spaces 11. At the inner side of the yoke, the channels 15 on the opposite sides are separated only by knife edges 16 which offer little or no obstruction to the stream of liquid and directs the stream into the respective channels. The inner end of the screw 3 is coned and also tends to deflect the impinging stream toward the chan-

nels. As a result of this formation, the components of the stream are directed, at high velocity, toward the inner ends of the spaces 11 and are discharged through these spaces against the underside of the secondary deflector with the results described above.

I claim:

1. In an atomizing spreader, the combination with a primary deflector comprising a plurality of narrow radiating arms and intervening open spaces, of a secondary deflector axially spaced from and of smaller radial extent than the said primary, said secondary deflector overlying the inner portions only of the said intervening spaces.

2. In an atomizing spreader, the combination with a primary deflector comprising a plurality of narrow radiating arms and intervening open spaces, the sides of said spaces converging toward the center of radiation, of a secondary deflector axially spaced from and of smaller radial extent than the said primary so as to overlie only the relatively restricted inner ends of said spaces, and notches in the other ends of the said radiating arms.

3. In a sprinkler head of the type comprising a body member having a discharge port and a yoke extending beyond and providing a support for a

deflector in line with said port; said deflector comprising a primary deflector element having narrow radiating arms and intervening spaces, means in the adjoining portion of the yoke for guiding a discharged liquid to the inner ends of said spaces, and a secondary deflector element relatively remote from the port and arranged to laterally deflect the liquid passing through the said inner ends of the spaces for impingement upon the particles of liquid passing through the outer portions of said spaces.

4. In an atomizing spreader adapted to be positioned in the path of a jet of liquid for atomizing and distributing the latter, the combination of a primary deflector comprising radial arms diverging slightly from a plane normal to the axis of the deflector toward the source of said jet, said arms having spaces between them together with space-forming notches at their tips, and a secondary deflector comprising a solid disc of smaller diameter, centered above said primary deflector and extending radially beyond the inner portions only of the spaces between said arms so as to deflect laterally at high velocity the intercepted portions of the streams of liquid that pass through the spaces of the primary deflector.

ARTHUR C. ROWLEY.
